SAFETY RAZOR

Kenneth H. Grange, London, England, assignor to
Wilkinson Sword Limited, London, England, a
British company

Filed Mar. 5, 1968, Ser. No. 10,856

Claims priority, application Great Britain Sept. 14, 1967

Term of patent 14 years

Int. Cl. D28—03

U.S. Cl. D95—3

Fig. 1.

Fig. 2.

Fig. 3.

FIGURE 1 is a perspective view from above and one side of a safety razor showing my new design;

FIGURE 2 is a perspective view thereof and showing the other side to that shown in FIGURE 1;

FIGURE 3 is an underside plan view thereof;

FIGURE 4 is a side elevational view thereof with the top cover of the safety razor in the open position; and

FIGURE 5 is an end view thereof with the top cover in the same position as in FIGURE 4.

The dominant features of the design reside in the fashioning of the handle with a gently expanding taper which, adjacent the head, flares laterally outward toward the ends of the underside of the head, and with front and rear plane faces which diverge outwardly toward but are spaced inwardly from the guard bars of the head.

I claim:

The ornamental design for a safety razor, as shown and described.
